Filed Dec. 13, 1968, Ser. No. 14,956

Term of patent 14 years

Int. Cl. D16—03, 04

U.S. Cl. D61—1

FIG. 1

FIG. 2

FIG.3

FIG.4

FIG. 5

FIG. 6

FIGURE 1 is a perspective view of the projector incorporating a reflecting mirror enclosure which is shown in the raised, operative, forward image projecting condition;

FIGURE 2 is a perspective view of the projector oriented as in FIGURE 1, but illustrating the reflecting mirror enclosure reoriented relative to the projector so as to project an image to one side rather than toward the front as shown in FIGURE 1;

FIGURE 3 is an overall environmental view of the projector shown with the reflecting mirror enclosure oriented as in FIGURE 1 and projecting an image forwardly onto a viewing screen which is depicted in dot-dash lines and forms no part of the invention;

FIGURE 4 is a front elevational view of the projector showing the reflecting mirror enclosure in the closed position;

FIGURE 5 is a side elevational view showing the reflecting mirror enclosure in the closed position; and,

FIGURE 6 is a plan view of the projector showing the reflecting mirror enclosure in the closed position.

I claim:

The ornamental design for a projector, as shown and described.
